JOSEPH RUDOLPH, JOSEPH ROSENZWEIG, AND DAVID ASCHKENAS, OF NEW YORK, N. Y.

HAND BAG

Application filed October 10, 1931. Serial No. 568,130.

The subject-matter of the present invention relates to hand bags and the improvements are directed to novel and unique means for mounting and positioning a pocket book or coin purse within the interior thereof so that said pocket book may be concealed from view when the hand bag is closed and which is readily accessible when said hand bag is opened.

10 As will presently appear it is proposed to provide an arrangement of the above-mentioned character without materially altering the interior of a hand bag and positively without changing the external appearance thereof.

20 A salient feature of the present invention resides in the provision of means in the form of a partition, or the like, said partition being suitably and permanently secured to one of the pleated ends of a hand bag and extending longitudinally of the latter to afford means for supporting a coin purse.

25 An essential object of the invention resides in the production of a partition of the above-mentioned character, said partition being recessed in the upper central portion thereof for the reception of a coin purse as aforesaid.

30 Another object is to provide novel clamping members adapted to be more or less permanently secured to one of the metal frames of a coin purse and adapted to cooperate with a portion of the above-mentioned partition to maintain the coin purse in a non-oscillatory position.

35 Still another object of the invention is to provide a finished article which is neat and attractive in appearance and which may be inexpensively manufactured, thus assuring its commercial success.

40 With these objects in view, together with others which will appear as the description proceeds, the invention resides in the novel formation, combination, and arrangement of parts, all as will be described more fully hereinafter, illustrated in the drawing, and particularly pointed out in the claims.

In said drawing:

45 Figure 1 is a perspective view of a hand bag in opened position and exposing our in-

vention, the closing flap of said bag being broken away.

Fig. 2 is a perspective view of one of the clamping members shown in Fig. 1.

50 Fig. 3 is a sectional detail, slightly enlarged, and taken on the line 3—3 of Fig. 1.

Fig. 4 is a fragmentary perspective view of our novel partition and illustrating a slightly modified form of clamping member employed at both ends of the coin purse.

55 Fig. 5 is a perspective view of said modified form of clamping member.

Fig. 6 is a sectional detail, slightly enlarged, and taken on the line 6—6 of Fig. 4.

60 Before presenting the invention in its detailed form, it is pointed out that quite frequently it is the practice for ladies to provide themselves with a hand bag and a coin purse or pocket book, both being individual items and usually the pocket book is simply 65 placed within the hand bag and treated as another article within said bag. When it becomes necessary to extract coins, or the like, from said pocket book, this operation necessitates the placing of the hand bag on a counter 70 or desk and under these conditions the hand bag is either forgotten or lost and becomes 75 the property of an unauthorized person.

75 As will presently appear, we propose to 80 permanently mount a pocket book within a hand bag whereby it becomes a substantial fixture thereof and whereby access to said pocket book may be had without temporarily removing the hand bag from the hands of the owner, or losing possession thereof.

85 Referring now more in detail to the accompanying drawing, wherein like characters of reference denote similar parts throughout the several views, let 5 and 6 indicate the front and rear walls, respectively, of a hand bag, 90 and 7 and 8 the end walls thereof, said walls being in the form of accordion pleats well-known in this art. While Figure 1 shows the hand bag in opened position it will be understood that the accordion pleats permit the 95 collapse of the bag to a relatively small area so that the closing flap 9, (broken away in Fig. 1), may be suitably affixed to the outer face of the front wall 5.

100 As shown in Fig. 1, we provide a partition-

like member 10, which extends longitudinally, centrally and vertically of the bag, as viewed in said Fig. 1, said partition having its lateral edges suitably secured to the opposite central pleat in the ends of the bag, as shown at 11 and 12, stitching, or the like, being adopted for this purpose. The lower edge of said partition extends to the bottom of the bag but is not fastened along its bottom edge. The central upper portion of said partition 10 is 10 cut away to form a recess 13, while the edges of the material bounding the three sides of said recess are turned back and stitched as shown at 14, thus forming sufficient material to serve as an anchorage for certain clamping members about to be described.

The coin purse, or pocket book, is designated by the numeral 15, the construction thereof being well-known in this art, in that we have the usual body portion, the metal frame members 16 and 17, which are usually U-shaped, and having their ends pivoted at 18 and 19 to permit access to said purse. The usual clasps 20 and 21 are provided to hold the frame members in close position. To 25 permanently mount said purse 15 in the recess 13, as pointed out in detail hereinbefore, and to affix the same to said partition 10, we have provided novel clamping means 22, (see Fig. 2), said clamping means being formed from a suitable piece of bendable material to present a channel portion 23 and a lateral portion 24, the latter being suitably affixed to the frame member 16, as by soldering, as 30 indicated at 25, (see Fig. 3). When said clamping means 22 have been suitably affixed to the ends of the frame member 16, the channel portion 23 is slipped over the top edge of the partition adjacent both sides of the recess 13 and the portions are then pressed to firmly and rigidly engage said edges. The purse is now in the position indicated in Fig. 1 with the bottom of the purse slightly below the bottom of said recess 13, but in a substantially erect position and this position is maintained when the clasps 20—21 are manipulated to swing down the frame member 17 to open said purse. Thus, there is no oscillation or pivotal movement of the purse as a 45 whole when the hand bag is opened or closed, or when the purse itself is opened for use.

The purse 25 shown in Fig. 4 is similar to purse 15, just described, the said purse 25 includes the frame members 16 and 17, also 55 pivoted at 18 and 19, and the partition 10 is provided with a recess 13, and hence the same numerals appearing in Fig. 1 have been applied to the similar parts shown in Fig. 4.

In the present instance the clamping member 26, (see Fig. 5), is a channel-formation throughout and said member is bent to provide the channel-like legs 27 and 28. As shown in Fig. 6, the leg 27 is affixed to the ends of said frame member 16, rivets 29 or 65 solder 30 being employed for the purpose, or

both. Said channel-like legs 27 and 28 are then fitted over the corners of the partition 10 at both sides of the recess 13 and after being pressed against the material firmly anchor said purse 25 in the position shown. Said clamping member 26 is thus very neat in appearance and admirably performs its function.

From the foregoing it will be seen that we have provided means whereby a purse may be associated with a hand bag without materially altering the construction of the latter and which precludes the danger of losing or mislaying said purse or bag.

While the present is a disclosure of the preferred embodiments of the invention, it is to be understood that the invention is not limited thereto, as various changes in the minor details of construction, proportion and arrangement of parts may be resorted to without departing from the spirit of the invention as defined in the appended claims.

We claim:

1. The combination with a hand bag having side walls and a purse including pivoted frame members, of a partition secured to the sidewalls of the bag, said partition having its central upper portion cut away to present a recess and a clamping member affixed to the ends of one of said frame members and having a channel portion clamped to the upper edges of the partition adjacent said recess to non-rotatably mount said purse in said recess.

2. The combination with a hand bag having side walls and a purse including pivoted frame members, of a partition secured to the sidewalls of the bag, said partition having its central upper portion cut away to present a recess and means for non-rotatably affixing one of the frame members to said partition, said means including a clamping member affixed to the ends of one of said frame members and having a channel portion clamped to the partition at its opposite edges in the recess and the upper edges of said partition adjacent said recess.

3. In a hand bag, a partition having a recess, a pocket book including pivoted frame members mounted in said recess, one of said frame members being non-rotatably affixed to said partition.

4. In a hand bag, a partition having a recess, a pocket book having pivoted U-shaped frame members mounted in said recess and means connecting said partition and one of said frame members whereby the pocket book is non-rotatably disposed within said recess.

In testimony whereof we affix our signatures.

JOSEPH RUDOLPH.
JOSEPH ROSENZWEIG.
DAVID ASCHKENAS.
